UNITED STATES PATENT OFFICE.

MASAO TANAKA, OF NEW YORK, N. Y.

HAIR-CLIPPER.

1,297,216.

Specification of Letters Patent. Patented May 22, 1917.

Application filed March 29, 1916. Serial No. 87,660.

To all whom it may concern:

Be it known that I, MASAO TANAKA, a subject of the Emperor of Japan, residing at New York, in the county and State of New York, have invented new and useful Improvements in Hair-Clippers, of which the following is a full, clear, and exact description.

My invention relates to devices of the kind known as hair clippers, and used for clipping hair, wool, furs, etc., at rapid rates of speed.

More specifically stated, my invention contemplates a hair clipper operated by power and provided with suction mechanism for removing the material as rapidly as the same is severed.

My invention relates more particularly to the form and arrangement of the various parts, for improving the general efficiency of the mechanism as hereinafter set forth in the specification and claims.

Reference is to be made to the accompanying drawings, forming a part of this specification, and in which like reference characters indicate like parts in all of the figures.

Figure 1 is a fragmentary plan of my device, parts being broken away.

Fig. 2 is a section on the line 2—2 of Fig. 4, looking in the direction of the arrows, and showing the cutting mechanism and parts adjacent thereto.

Fig. 3 is a fragmentary side elevation of a part of the casing and a gear box mounted thereupon.

Fig. 4 is a fragmentary view of the device, showing it partly in side elevation and partly in a substantially central vertical section.

Fig. 5 is a section on the line 5—5 of Fig. 4 looking in the direction of the arrows, and showing the exhaust fan.

Fig. 6 is a detail view, showing a cross section on the line 6—6 of Fig. 1.

Fig. 7 is a section on the line 7—7 of Fig. 4, looking in the direction of the arrow.

Fig. 8 is a perspective of the retaining bag, for storing the material severed.

Fig. 9 is a fragmentary perspective of the cutting mechanism and the exhaust passage.

Fig. 10 is a perspective of the finger plate forming a part of the cutting mechanism.

Fig. 11 is a perspective of the cutter plate.

Fig. 12 is a perspective of the rocking lever for actuating the cutter plate.

A handle portion 13, having a cross sec-

tion indicated in Fig. 6, carries a hollow flat portion 14, which has a cross section indicated in Fig. 7 and is provided with a floor 14^a and with an upturned or flaring end portion 15. Above the hollow flat portion 14 is a casing plate 16, provided with a foot portion 16^a secured directly to the top of the portion 14.

Just above the portion 14 is a bevel gear 17, provided with teeth 18 and covered by the casing plate 16. This bevel gear is secured rigidly upon a short revoluble shaft 19. Engaging the bevel gear is a bevel pinion 20, which carries a stub shaft 21 extending through the adjacent wall of the casing plate 16 and thus journaled thereto.

Detachably mounted upon the under side of the floor 14^a is a finger plate 22, carrying a pivot pin 23 extending upwardly from it and having in this instance the form of a screw. Fastening screws 24 secure one end of the finger plate to the handle portion 13.

The finger plate 22 is provided with a number of fingers 25 integral with it and having the general form of a row of teeth. The finger plate 22 carries a pair of guide lugs 26 extending upwardly through slots 26^a in a movable cutting plate 27, as indicated more particularly in Fig. 2. The cutting plate 27 carries a number of cutting blades 28 integral with it and having the general form of a row of teeth. The cutter plate is also provided with a pair of downturned ends 29 which rest upon the finger plate 22, the row of cutting blades 28 also resting upon the finger plate.

Journalized upon the pivot pin 23 is a rocking lever 30 having the form shown more particularly in Figs. 2 and 12. It has a pivot hole 31 for receiving the pivot pin 23. It also has a head 32, which extends into a recess 32^a with which the cutting plate 27 is provided, as shown in Fig. 2. The rocking lever 30 is also provided with downturned bearing members 33, 34, which rest upon the finger plate 22, and with a recess 35. Fitting loosely into this recess is a cam 36, secured rigidly upon and carried by the revoluble shaft 19.

A yoke 36 is connected by a hinge 37 to one edge of the finger plate 22, as will be understood from Fig. 7. The yoke 36 extends across the finger plate and by means of a thumb screw 48 is detachably secured to the edge of the finger plate at a point sub-

stantially opposite the hinge 37. By removing the thumb screw 38, the yoke 36 can be swung upwardly upon the hinge 37 as a center, and this facilitates the removal 5 of the finger plate 22.

An adjusting screw 38 extends through the yoke 36 and is encircled by a spiral spring 40. By turning the screw 39 the finger plate 22 is adjusted bodily in relation 10 to other parts, and the degree of pressure between the movable and stationary cutting members is regulated accordingly.

Integral with the handle portion 13 is a pocket 40, having a peripheral flange 41, 5 and secured to the pocket by aid of this flange is a fan casing 42. Extending through this fan casing is a revoluble shaft 43 carrying a fan 44 and a bevel pinion 45. Engaging this bevel pinion 45 is another 20 bevel pinion 46. These bevel pinions 45, 46 are located within a gear box 47. Adjacent this gear box is a bearing 48 and supported and guided by this bearing is a flexible shaft 49 upon which the bevel pinion 47 is rigidly 25 mounted, so as to turn with the flexible shaft. This extends through the gear box 47 and through bearings 50, 51 as well as through the handle portion 13, and carries the bevel pinion 20.

30 Power is applied to the flexible shaft 49 in any convenient source, not shown. The shaft being caused to rotate, the fan 44 is driven through the medium of the bevel pinions 46, 45, and air is drawn through the 35 apparatus as indicated by the arrows in Fig. 4.

The rotation of the flexible shaft also causes the pinion 20 to turn, and this causes the rotation of the bevel gear 17 and shaft 40 19. The cam 36 thereupon communicates a rocking movement to the lever 30. This causes the cutting plate 27 to slide back and forth across the finger plate 22, so that the blades 28 are moved relatively to the fingers 45 28. The hair or other material severed by the cutting is sucked into the open or flared end 15 and drawn through the hollow flat portion 14 and handle portion 13 to the pocket 40 whence it passes upwardly into 50 the fan casing and is thence driven out, as may be understood from the arrows shown in Fig. 4. The pocket 40 is held in position by aid of bolts 42 as shown in Fig. 3.

The fan casing is provided with a neck 52 55 carrying a pin 53. A bag 54 (see Fig. 8) is used for receiving and temporarily storing the hair or other material severed by the apparatus. The bag 54 is provided with a neck 55, which fits concentrically upon the 60 neck 52, the neck 55 having a slot 56 for receiving the pin 53 in order to prevent the bag 54 from turning bodily in relation to other parts.

To facilitate removal of the hair or other 65 material the bag 54 is provided with purse

jaws 57, 58. The bag is also provided with clasps 59 for holding these jaws together except when the bag is to be opened.

The operation of my device is as follows:

The parts being assembled and arranged as above described and properly adjusted, power is applied to the revoluble shaft 49 so as to turn the same continuously and thus cause the various movable parts to perform 70 their functions. The operator now grasps the handle portion 13 and brings the cutting members into engagement with the hair or other material to be cut. To facilitate the work, one moves the device as may suit his 75 convenience, for instance passing it over or around a person's head from which hair is to be cut. The severed material is drawn through the handle portion 13 as elsewhere described, and ultimately discharged into 80 the bag 54.

The parts are so formed and positioned that while the device is in use the fan casing does not obstruct the operator's view. The handle portion 13 is tangential to the 85 fan casing, as shown in Fig. 1, and is slightly askew relatively to the general direction in which the fingers 25 and cutting blades 28 extend. The parts are thus positioned very favorably for enabling the operator to hold the handle portion 13 in his 90 right hand while he can observe accurately every detail of the cutting operation.

I claim:

1. In a hair clipper, the combination of a 100 frame provided with a hollow handle portion of longitudinal form, cutting mechanism carried by said frame and disposed adjacent one end of said handle portion, a casing carried by said handle portion and located at the end thereof opposite said cutting mechanism, a pocket carried by said casing and communicating therewith, said pocket being separate from said casing and located below the same, a revoluble fan 105 mounted within said casing and located immediately above said pocket in order to facilitate the travel of cuttings of hair from said handle portion and thence through said fan, driving mechanism for actuating said 110 cutting mechanism and said fan, and a receptacle connected with said casing for receiving said cuttings as discharged by said fan.

2. In a hair clipper, the combination of a 115 handle of tubular form, a casing mounted upon one end of said handle and provided with a flat hollow portion, cutting mechanism located within said flat hollow portion and arranged to deliver cuttings of hair into 120 said handle, a casing plate carried by said casing and spaced slightly therefrom, a shaft connected to said cutting mechanism for the purpose of actuating the same, said shaft being journaled at one of its ends to 125 130

said casing plate and extending through the space between said casing and said casing plate, a gear wheel mounted upon said shaft and located within said space between said casing and said casing plate, a pinion engaging said gear wheel for the purpose of actuating the same, a flexible shaft connected to said pinion and extending through said handle, and a suction fan located at the end of said hollow handle opposite said first-mentioned casing for receiving and discharging the cuttings severed by said cutting mechanism. 10

MASAO TANAKA.
